OSCAR V. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

INDICATOR FOR FALLEN DROP WIRES

Application filed February 21, 1930. Serial No. 430,407.

This invention relates to looms in which a warp stop motion is provided and in which a drop wire falls upon the breakage of a warp thread. In silk looms or any other looms using very fine warps, the drop wires are banked very closely together and it is often difficult to locate the fallen wire after the loom stops.

It is the object of my invention to provide an indicating device by which the location of the fallen drop wire may be quickly discovered and readily disclosed to the weaver.

In the preferred form of the invention, the disclosure or indication is made by a small electric bulb which is illuminated when contact is made with the fallen drop wire.

My invention further relates to arrangements and combinations of parts which will be hereinafter described and more particularly pointed out in the appended claims.

A preferred form of the invention is shown in the drawings, in which

Fig. 1 is a plan view of a stop motion embodying my improvements;

Figs. 2 and 3 are sectional side elevations, taken along the lines 2—2 and 3—3 in Fig. 1;

Fig. 4 is a detail front elevation, looking in the direction of the arrow 4 in Fig. 3;

Fig. 5 is a detail sectional view, taken along the line 5—5 in Fig. 3; and

Fig. 6 is a detail sectional view, taken along the line 6—6 in Fig. 1.

Referring to the drawings, I have shown portions of a loom frame 10 supporting brackets 12 in which angle bars 14 are mounted. The bars 14 provide supports for a stop motion comprising several banks of drop wires W arranged on cross rods 16. As shown in the drawings, the stop motion is of the electrical type but my invention is not limited to any particular type of stop motion and is equally applicable to many types of mechanically indicated stop motions.

The wires W are strung on the warp threads T and are maintained in raised position so long as the threads are unbroken. If a thread breaks, the associated drop wire W falls to the position indicated at W' in Fig.

3. In this position, the drop wire closes a

circuit through the two parts of its supporting bar and thus gives an indication by which the loom is stopped.

The construction of the stop motion and the method of operation thereof forms no part of my present invention, which relates particularly to means for indicating the position of the fallen drop wire W'.

For this purpose a cross bar or support 20 is clamped in downwardly extending projections 21 of the brackets 12 previously described. The bar 20 may be secured in the projections 21 by clamping plates 22 (Fig. 2) and clamping screws 23. The bar is preferably insulated electrically from the projections 21 and plates 22, as indicated at 24 in Fig. 2.

A wire 25 (Fig. 1) connected to one side of an electric circuit is secured to the bar 20 between the projections 21. A support 30 is freely slideable on the bar 20 and is provided with a rearwardly extending bracket or plate 31 (Fig. 3) on which a lamp socket 32 is mounted. A small electric bulb is inserted in the socket 32 and one terminal of the socket is connected through the bracket 31 and support 30 to the cross bar 20. The other terminal of the socket 32 is connected by a wire 40 to a contact member 41 mounted on but insulated from the sliding support 30.

The method of mounting the member 41 on the support 30 and securing the wire 40 thereto is clearly indicated in Fig. 5. Strips of insulating material 42 and 43 are provided at each side of the support 30 and an insulating bushing 44 surrounds the binding screw 45. The other side of the electric circuit is grounded to the loom frame and is connected through the stop motion supports 80 to the fallen drop wire W'.

As the support 30 and member 41 are moved along the cross bar 20 under the banks of drop wires W, the member 41 will engage any fallen drop wire W' and such engagement completes an electric circuit through the electric bulb 33, causing the bulb to be immediately illuminated, thus clearly indicating the position of the fallen drop wire.

As the bar 20 and sliding support 30 are

below the warp threads T, it is not very convenient for the weaver to grasp and move the support 30. Accordingly I have provided means by which the support may be readily moved from a point above the warp.

For this purpose I provide brackets 50 (Fig. 6) clamped to end portions of the cross bar 20 and having upper and lower bushings or guide eyes 51 and 52 for a cord 54 which extends through the brackets and guide eyes and has its opposite ends secured to the sliding support 30, as indicated in Fig. 1.

The brackets 50 extend up through the warp between certain of the warp threads and the upper bushings 51 are above the warp. Consequently the upper run of the cord 54 is also above the warp and in a position readily accessible by the weaver from either side of the loom. The electric bulb 33, while below the warp, can be readily seen through the warp when illuminated by contact with a fallen drop wire.

I have thus provided for easy and rapid indication of the location of a fallen drop wire, which indication may be given without requiring the weaver to make any search for the fallen drop wire or to attempt to look under the warp and stop motion to determine the position of the fallen wire. The weaver is thus enabled to determine very quickly whether or not the loom has been stopped by the warp stop motion and if so, the exact location of the fallen drop wire.

Not only does the light indicate the general location of the fallen wire, but the fallen wire is rocked upon the contact bar 16 when engaged by the cross bar 41 and such rocking movement of the fallen wire separates the adjacent drop wires and warp threads, giving a further and more specific indication of the exact location of the fallen wire.

Having thus described my invention and the advantages thereof, I do not wish to be limited to the details herein disclosed, otherwise than as set forth in the claims, but what I claim is:

1. In a loom having a warp stop motion using a plurality of drop wires, an indicating device comprising a contact member separate and additional to said warp stop motion and manually movable along a predetermined path crosswise of the loom below the stop motion, and means to give a visual indication when said member engages a fallen drop wire.

2. In a loom having a warp stop motion using a plurality of drop wires, an indicating device comprising a contact member movable crosswise of the loom below the stop motion, an electric bulb, and an electric circuit for said bulb adapted to be closed when said member engages a fallen drop wire.

3. In a loom having a warp stop motion using a plurality of drop wires, an indi-

cating device comprising a contact member movable crosswise of the loom below the stop motion, an electric bulb movable with said member, and an electric circuit for said bulb adapted to be closed when said member engages a fallen drop wire.

4. In a loom having a warp stop motion using a plurality of drop wires, an indicating device comprising a contact member separate and additional to said warp stop motion and movable along a predetermined path crosswise of the loom below the stop motion, means to give a visual indication when said member engages a fallen drop wire, and manual means to move said member crosswise of the loom.

5. In a loom having a warp stop motion using a plurality of drop wires, an indicating device comprising a contact member separate and additional to said warp stop motion and movable along a predetermined path crosswise of the loom below the stop motion, means to give a visual indication when said member engages a fallen drop wire, and manually operated means to move said member crosswise of the loom.

6. The combination in a loom as set forth in claim 5, in which said manually operated means comprises a cord extending crosswise of the loom above the warp and accessible from either side of the loom.

7. The combination in a loom as set forth in claim 5, in which said manually operated means comprises a cord extending crosswise of the loom above the warp and accessible from either side of the loom, the ends of said cord being connected to said contact member below the warp and said cord being effective for movement of said member in both directions.

8. In a loom having a warp stop motion using a plurality of drop wires, an indicating device comprising a contact member movable crosswise of the loom below the stop motion, an insulated cross bar mounted in fixed position, a support for said member slidable on said cross bar, an electric bulb mounted on said support, an electric connection from said cross bar to one terminal of said bulb, an electric connection from the other terminal of said bulb to said contact member, said member being insulated from said slidable support and said cross bar being connected to one side of an electric circuit while the fallen drop wire is connected through the stop motion to the other side of the circuit.

9. In a loom having a warp stop motion using a plurality of drop wires, an indicating device comprising a contact member movable crosswise of the loom below the stop motion, and means to give a signal when said member engages a fallen drop wire.

10. In a loom having a warp stop motion using a plurality of drop wires, an indicating device comprising a contact member separate

and additional to the warp stop motion and manually movable along a predetermined path crosswise of the loom below the stop motion and relative thereto, said contact member causing rocking movement of the fallen drop wire on engagement therewith, whereby adjacent drop wires and warp threads are separated.

11. In an electric warp stop motion, a contact bar mounted in fixed position, a plurality of drop wires mounted thereon, and manually operated means separate and additional to said warp stop motion and movable along a fixed path crosswise of the loom and relative to said contact bar, said means being effective to engage and rock a fallen drop wire about its point of contact with said contact bar, thereby separating adjacent drop wires and warp threads and indicating the location of the broken warp thread.

20 In testimony whereof I have hereunto affixed my signature.

OSCAR V. PAYNE.
